Primary Examiner — Paula Allen Greene*(74) Attorney, Agent, or Firm* — Cantor Colburn LLP(57) **CLAIM**

The ornamental design for a neckband earphone, as shown and described.

DESCRIPTION

FIG. 1 is a front perspective view of a neckband earphone, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another front view thereof in an alternative configuration.

The broken lines illustrating portions of the neckband earphone form no part of the claimed design.

1 Claim, 8 Drawing Sheets(56)
